UNITED STATES PATENT OFFICE.

JOHN HIGSON, OF LONDON, ENGLAND, ASSIGNOR OF ONE-HALF TO WILLIAM EVANS, OF KEARNY, NEW JERSEY.

BICYCLE-BRAKE.

SPECIFICATION forming part of Letters Patent No. 606,626, dated June 28, 1898.

Application filed October 5, 1896. Serial No. 607,879. (No model.) Patented in England August 14, 1895, No. 15,308.

To all whom it may concern:

Be it known that I, JOHN HIGSON, a citizen of Great Britain, residing at 97 East Ferry road, Cubitt Town, London, England, have 5 invented certain new and useful Improvements in Bicycle and Velocipede Brakes; and I do hereby declare the following to be a full, clear, and exact description of the invention, such as will enable others skilled in the art 10 to which it appertains to make and use the same, reference being had to the accompanying drawings, and to letters of reference marked thereon, which form a part of this specification.

15 This invention was patented in Great Britain August 14, 1895, No. 15,308.

The object of this invention is to provide a 20 brake for bicycles, &c., that will be more perfectly and easily controlled by the foot of the rider, to provide a more simple construction whereby the joints and parts are reduced in 25 number and liability to get out of order is lessened, and to secure other advantages and results, some of which may be referred to 25 hereinafter in connection with the description of the working parts.

The invention consists in the combined foot-rest and foot-brake and in the arrangements and combinations of parts, all substantially 30 as will be hereinafter set forth and finally embraced in the clauses of the claim.

35 Referring to the accompanying drawings, in which like letters of reference indicate corresponding parts in each of the views, Figure 1 is a front elevation of the improved device. Fig. 2 is a side elevation of the same, showing it attached to the bicycle-frame; and Fig. 3 is a plan of the same.

In said drawings, *a* indicates the clamps, 40 adapted to be screwed to the front fork *A* of the bicycle-frame. Each of the said clamps consists of two clamp members *a'* *a''*, which are more or less hook-shaped or otherwise made to conform with the shape of the fork 45 and hold thereto when brought into clamping relation, *a'''* being a clamp-screw for holding the said parts in said relation.

Upon the members *a'* of the clamps are secured oppositely-extending horizontal foot- 50 supports *b* *b*, which are preferably of sheet spring-steel metal bent longitudinally into a

V shape, as shown in Fig. 2, the upper edges being serrated, so as to prevent the shoe from slipping.

The foot-supports *b* *b* are suitably shaped 55 at their bases to serve as pivotal bearings for the brake-arms *c* *c*, which latter are arranged on said supports *b* and extend forwardly from the same and are bent to approach one another, as shown in Fig. 3, to receive a brake-shoe *d* 60 between. The said arms *c* *c* are perforated to provide bearings for the axial shaft *d'* of said brake-shoe and are connected or joined together by a rod or bar *g*, so that said arms will work together with firmness. The brake- 65 shoe *d* is cylindrical and may be turned on the axial shaft when worn by loosening the clamping means *d''*, which are preferably ordinary nuts. Beyond the said bearings for the brake-shoe *d* the said arms *c* *c* are turned 70 outwardly or away from said roller, as at *c'*, and serve as foot-supports when pressing down the brake-shoe. Said supports *c'* lie forward of, but approximately parallel with, the foot-supports *b*, so that the feet resting 75 on the foot-supports *b* may be inclined downwardly and at the fore part of the foot press upon the said supports *c'* to force the brake-shoe *d* downward against the wheel *e*, so that a braking action is effected, adapted to retard 80 or stop the rapid movement of the said wheel. Springs *f* are also secured upon the clamp members *a'* and serve to raise the said arms *c* *c*, and with them the brake-shoe *d*, and hold them normally away from the wheel *e*, so that 85 there will be no braking action excepting when the pressure of the foot is brought to bear thereon. The arms *c'* are also serrated at their upper edges to prevent the feet from slipping therefrom.

In lieu of a cylindrical or roller shape *d* I 90 may employ any other form of brake-shoe convenient and suitable for the purpose. In operating the device the rider after removing his feet from the pedals preliminary to stopping the machine places them upon the supports *b* *b*, which may be used at any time, even when the brake is not to be applied.

When it is desired to stop the machine, the rider simply presses down the back or heel 100 part of the foot or feet upon the arms *c'*, so that the brake-shoe is pressed against the pe-

riphery of the vehicle-wheel. The pressure immediately retards or stops the rotation of the said wheel.

The brake by its simplicity of construction 5 can be fixed to the frame of the vehicle with great facility by means of the clamp-screws a'' , and may be removed, of course, with equal facility when not needed.

Having thus described the invention, what 10 I claim as new is—

1. The combination, in a bicycle-brake, with the clamps a , having foot-supports b , which serve as pivots for forwardly-projecting arms c , c , of said arms c , c , pivoted upon said foot- 15 supports and extending forward therefrom and at their extremities bent oppositely outward to form a second pair of foot-supports c' , c' , a brake-shoe arranged between said arms and having bearings thereon, substantially 20 as set forth.

2. The improved brake device for bicycles comprising clamps a , a , having foot-supports b , b , extending laterally from said clamps and serving as pivots, arms c , c , pivoted on said laterally-extending supports bent toward one 25 another and providing bearings for a brake-shoe and forward of said brake-shoe, being bent oppositely away from one another and forming foot-supports c' , c' , a brake-shoe secured between said arms c , c , springs f , and 30 a connection g , for said arms, substantially as set forth.

In testimony that I claim the foregoing I have hereunto set my hand this 21st day of September, 1896.

JOHN HIGSON.
